DRAFT RIGGING

John H. Link, Merion, Pa., assignor to W. H. Miner, Inc., Chicago, Ill., a corporation of Delaware

Application February 5, 1932. Serial No. 591,061

12 Claims. (Cl. 213—9)

This invention relates to improvements in draft riggings especially adapted for mine cars.

One object of the invention is to provide a draft rigging of simple design, which may be economically manufactured and which is adapted to successfully cushion both the draft and buffering shocks to which mine cars are subjected in service.

A more specific object of the invention is to provide a draft rigging of the character specified in the preceding paragraph comprising a minimum number of parts by utilizing the cushioning means which is used to absorb the buffering shocks to also absorb the draft shocks, and employing a single member in the form of a transverse beam having buffering heads at opposite ends thereof and a coupler connection intermediate its ends to transmit the buffering and draft shocks to the cushioning means.

A still further object of the invention is to provide in a draft rigging for mine cars means for absorbing both draft and buffering shocks, wherein the draft and buffering strains are distributed through the car structure by supporting the shock absorbing means on the side sills of the car and imparting both the buffering and draft forces thereto by means of a single member having buffering heads at opposite ends thereof and a draft connection centrally between the ends.

Other objects of the invention will more clearly appear from the description and claims hereinafter following.

In the drawings, forming a part of this specification, Figure 1 is a part plan and part horizontal sectional view of a mine car, illustrating my improvements in connection therewith, the horizontal section being taken through the underframe structure of the car. Figure 2 is a longitudinal, vertical, sectional view, corresponding substantially to the line 2—2 of Figure 1. Figure 3 is a transverse, vertical, sectional view, corresponding substantially to the line 3—3 of Figure 1. Figure 4 is a front elevational view, partly broken away, looking from the left in Figure 1. Figure 5 is a horizontal, longitudinal, sectional view through the underframe structure of a mine car, illustrating another embodiment of my invention, said view being partly broken away. Figure 6 is a longitudinal, vertical, sectional view, corresponding substantially to the line 6—6 of Figure 5, said view showing certain parts in elevation. And Figure 7 is a front elevational view, partly broken away, looking from the left in Figure 5.

Referring first to the embodiment of the invention illustrated in Figures 1 to 4 inclusive, A design-

nates generally the body of the mine car. The car underframe structure is provided with pairs of longitudinally disposed sill members at opposite sides thereof, the sill members of each pair comprising an inner sill 10 and an outer sill 11. As clearly shown in Figure 1, the outer sill member is longer than the sill 10 and projects outwardly beyond the same at opposite ends of the car. The sills 10 and 11 are fixed to the car body in any well-known manner. At the outer ends of the car underframe structure, the sills 10—10 of the two pairs are connected by a transverse member 12 reinforced by securing angle plate members 13—13. The member 12 at each end of the car is inset with respect to the sills 10—10, thereby providing a pocket for a purpose herein-after pointed out.

The sill members 10 and 11 of each pair are provided with inner stop lugs 14—14 and an outer stop casting 15, which are fixed thereto. The inner stop lugs 14—14 are of similar design, each having a transverse web 16, which forms the rear stop member proper, and a forwardly extending section 17 embracing the inner end of the yoke. The outer stop casting 15, which is secured to the sills 10 and 11, has a transverse stop shoulder 18 adjacent to the sill 10 and a stop shoulder 118 adjacent to the sill 11 and in transverse alignment with the stop shoulder 18. The portion of the casting 15, which is secured to the sill 11, extends outwardly beyond the end of this sill and has a shouldered section 19 formed at the outer end thereof, which abuts the end face of said sill. The casting 15 has top and bottom walls 20—20, between which the corresponding end of the transverse pressure transmitting beam hereinafter more fully described is guided.

At each end, the mine car is provided with a pair of shock absorbing members 21—21 which, in the present case, are shown as friction mechanisms, each comprising the usual friction shell and cooperating wedge actuated friction elements. Each shock absorbing mechanism 21 cooperates with a front follower plate 22.

The buffering and draft shocks to which the mine car is subjected are transmitted to the shock absorbing mechanisms 21—21, a transverse beam member B and a pair of yoke members C—C operatively connected thereto being employed at each end of the car to transmit the buffering and draft forces to the shock absorbing mechanisms 21—21 at the corresponding end of the car.

Each transverse beam member B comprises a

central section 23, which is offset inwardly with respect to the opposite ends of the beam member. The section 23 comprises a pair of inwardly converging portions, as clearly shown in Figure 1, said inwardly converging portions being accommodated within the pocket formed by the inset member 12 at the corresponding end of the car. Between the ends, each beam member B is provided with a coupler hook 24, which is preferably pivoted thereto, being secured by a pin 35 or other well-known securing means. At opposite ends, the beam B is formed with buffing heads 26—26 projecting outwardly therefrom. Each head 26 is formed integral with the corresponding end of the beam. Rearwardly and in alignment with each head 26, the member B has a rearwardly projecting shank section 27, which abuts the corresponding follower plate 22 of the shock absorbing means between the sills 10 and 11 at the same side of the car. The shank portion 27 at each end of the beam B is connected to the corresponding yoke member C by means of a vertical key or pin 28 extending through the shank 27 and longitudinally disposed slots 29—29 in top and bottom members 30—30 of the yoke C.

The yoke C has spaced side arms 31—31 connected by a transverse rear end section 32, the end section 32 cooperating with the rear stop members 16—16. At the forward ends, the arms 31—31 are connected by the top and bottom members 30—30, as clearly shown in Figures 1 and 2. The shock absorbing mechanism 21 at each side of the car is disposed within the corresponding yoke member C and is slidably supported by a transversely extending saddle plate 33, which is supported by the sills 10 and 11. As shown in Figure 3, the saddle plate 33 is supported at the inner end from the sill 10 by means of a strap bracket 34 secured to the bottom of said sill and having a downwardly off-set central section receiving the corresponding end of the saddle plate. The opposite end of the plate 33 is secured to the sill 11 by an angle bracket 35 riveted to the outer face of the sill and the upper face of the outer end of the saddle plate 33.

The normal position of the parts of the draft rigging is shown in Figures 1 and 2. In this position, the inner end of each yoke C bears on the rear stop members 16—16, and the front follower plate 22 of the shock absorbing means bears on the stop shoulders 18 and 118 of the front stops at the corresponding side of the car. The connecting pins 28—28 of the beam B and the yoke members C—C are at the outer ends of the slots 29—29 of the yokes.

The operation of my improved railway draft rigging is as follows: Upon a buffing force being transmitted to the buffing heads 26—26, or either of them, the beam B is forced inwardly of the car, thereby carrying the followers 22—22 rearwardly therewith and compressing the shock absorbing mechanisms 21—21 against the rear end sections 32—32 of the yokes C—C. Inasmuch as the yokes C—C are held against rearward movement by the rear stops of the corresponding sill members, the shock absorbing mechanisms will be compressed, thereby cushioning the blows. When a draft or pulling action is applied to the coupler hook 24, the beam B at the corresponding end of the car will be pulled outwardly. This movement will be transmitted to the yokes C—C by the connecting pins or keys 28—28, thereby pulling the shock absorbing mechanisms 21—21 forwardly and compressing the same against the

front follower plates 22—22, which plates are held stationary by the outer stops of the sills.

Referring next to the embodiment of the invention illustrated in Figures 5, 6, and 7, the general construction of the mine car is substantially the same as that hereinbefore described in connection with Figures 1 to 4 inclusive. The underframe structure of the car illustrated in Figures 5, 6, and 7 comprises pairs of longitudinally extending sills at opposite sides of the car, which are arranged similarly to the sills 10 and 11. The members of the pair of sills of the car shown in Figures 5, 6, and 7 are indicated by 110 and 111 respectively. The sills 110 are connected by a transverse end member 112, which is inset from the outer ends of these sills. The sill 111 terminates short of the outer end of the car and is connected to the corresponding inner sill 110 by a bottom plate 149, which plate has an angle member 150 secured thereto. On the inner side, at the outer end each sill 111 carries a stop member 151 which is preferably riveted thereto and to the bottom plate 149. The stop member 151 has a pocket 152 at the outer end thereof, which is adapted to accommodate the inner end of the friction shell member of a shock absorbing mechanism 121. At the outer end, each sill member 110 has a transverse combined stop and guide member 153 secured thereto and to the corresponding bottom plate 149. On the inner side, the guide member 153 is provided with top and bottom spaced flanges 154—154, which embrace the corresponding end section of the transverse beam member D, which corresponds to the beam member B hereinbefore described in connection with Figures 1 to 4 inclusive.

The beam member D has an inwardly offset central section 123 to which the coupler hook 124 is fixed. At the opposite ends, the beam member D is formed with buffing heads 126—126, which are similar to the heads 26—26 shown in Figures 1, 2, and 4. At opposite ends, rearwardly of each buffing head 126 the beam D is provided with top and bottom rearwardly extending spaced arms 155—155 and an intermediate arm 156. The arm 156, as clearly shown in Figure 6, is shorter than the arms 155 and has the inner end thereof bearing directly on the front follower plate 122 of the corresponding shock absorbing mechanism. The stop and guide casting 153 is provided with top and bottom spaced webs 157—157, which form continuations of the webs 154—154 and embrace the central member 156 at the corresponding side of the beam D. The webs 157—157, as clearly shown in Figure 6, are disposed between the central member 156 and the top and bottom arms 155—155, thereby forming guide means for the corresponding end of the beam D.

In the normal position of the parts, the front follower 122 of each shock absorbing mechanism bears directly on the rear edges of the webs 157—157, these webs thus forming the front stop members for the rigging. The top and bottom arms 155—155 at each end of the beam D serve as connecting means to transmit the draft forces to the shock absorbing mechanism. As shown, each friction shell of the two shock absorbing mechanisms is provided with top and bottom trunnions 158—158, which work in slots 159—159 in the top and bottom arms 155—155 at the corresponding end of the beam D.

The operation of the rigging shown in Figures 5, 6, and 7 is as follows: Buffing forces received by the buffing heads 126—126 at opposite ends 150

of the beam D are transmitted to the shock absorbing mechanisms 121—121 through the followers 122—122 by the arms 156—156. In a buffering action, each shock absorbing mechanism 5 is compressed against the rear stop member 151. When a pulling force is applied to the coupler hook 124, the beam D is pulled outwardly and this movement is imparted to the friction shells 10 of the shock absorbing mechanisms 121—121 through the connections provided by the arms 155—155 and 155—155 at opposite ends of the beam D. During the outward movement of the shells 15 of the shock absorbing mechanisms 121—121, the mechanisms will be compressed against 15 the front followers 122—122, which are held stationary by the outer stop members.

From the preceding description taken in connection with the drawings, it will be seen that I have provided a simple and efficient shock absorbing 20 means for mine cars, which is effective in both buff and draft, wherein the structure is of simple and economical design, a transverse beam member at each end of the car being employed to transmit both the draft and buffering shocks to the 25 shock absorbing mechanisms. A further advantage of my improved design is that a minimum amount of space is occupied by the shock absorbing mechanism, the same being placed between the pairs of longitudinal sill members which are 30 located at opposite sides of the mine car under-frame.

I have herein shown and described what I now consider the preferred manner of carrying out my invention, but the same is merely illustrative 35 and I contemplate all changes and modifications that come within the scope of the claims appended hereto.

I claim:

1. In a draft rigging for cars, the combination 40 with a pair of shock absorbing mechanisms at opposite sides of the end of the car; of a transversely disposed pressure transmitting member at said end of the car, said pressure transmitting member having outwardly projecting buffering heads at opposite ends thereof; a coupler connection on said member between the ends thereof; means for transmitting buffering shock from said member to said shock absorbing mechanisms; and yoke means connected to opposite ends 45 of said member and enclosing said shock absorbing mechanisms for transmitting pulling forces to said mechanisms.

2. In a draft rigging for cars, the combination 55 with shock absorbing means at opposite sides of the end of the car; of a beam member extending transversely of the car, said beam member having outwardly offset opposite end sections presenting buffering heads rigid therewith; a coupler hook connected to said beam midway between the outwardly offset sections thereof; means at each end 60 of the beam actuated by said beam and engaging the outer end of the shock absorbing means at the corresponding side of the car for compressing the same upon inward movement of the beam; and means connected to said beam engaging the inner end of said shock absorbing means for compressing the same upon outward movement of said beam.

3. In car construction, the combination with 70 pairs of sills at opposite sides of the car extending lengthwise thereof; of stop means on each of said pairs of sills; shock absorbing means at opposite sides of the car buttressed against the stop means on said pairs of sills respectively in both buff and draft; and a member movable outwardly

of the car in draft and inwardly toward the car in buff, said member being operatively connected to all of said shock absorbing means for transmitting both draft and buffering forces to said shock absorbing means.

4. In car construction, the combination with 80 pairs of sills at opposite sides of the car extending from end to end of the car; of stop means on each pair of sills; shock absorbing means at each end of the car at opposite sides thereof buttressed against the corresponding stop means of the sills respectively in both buff and draft; a transversely extending pressure transmitting beam operatively connected at opposite ends to said shock absorbing means to transmit both draft and buffering forces thereto, said beam having buffering faces at opposite end sections thereof; and a coupler connected to said beam between the ends of the same.

5. In car construction, the combination with 85 pairs of longitudinally extending sills at opposite sides thereof; of stop means on each pair of sills; shock absorbing means at opposite sides of the car buttressed against said stop means of the sills respectively in both buff and draft; a transversely disposed pressure transmitting beam at 100 each end of the car, said pressure transmitting beam having outwardly projecting fixed buffering heads at opposite ends thereof; a coupler connected to each beam between the ends of the same; and means for transmitting draft and buffering shocks from said beams to said shock absorbing mechanisms.

6. In car construction, the combination with 105 pairs of longitudinally extending sills at opposite sides thereof; of stop means on each pair of sills; shock absorbing means at opposite sides of the car buttressed against said stop means of the sills respectively in both buff and draft; a transversely disposed pressure transmitting beam at 110 each end of the car, said pressure transmitting beam having outwardly projecting buffering heads at opposite ends thereof; a coupler connected to each beam between the ends of the same; means for transmitting buffering shocks from said beams 115 to said shock absorbing mechanisms; and yoke means connected to opposite ends of each of said beams and enclosing the shock absorbing mechanisms at the corresponding end of the car and adapted to transmit pulling forces to said mechanisms.

7. In a draft rigging for cars, the combination with a pair of shock absorbing mechanisms at opposite sides of the end of the car; of a transversely disposed pressure transmitting member at 120 said end of the car, said pressure transmitting member having outwardly projecting buffering heads at opposite ends thereof; a coupler connection on said member between the ends thereof; rearwardly extending arms on said member at 125 opposite ends thereof engaging the corresponding shock absorbing mechanism for transmitting buffering shocks thereto; and means having lost motion connections with said member for transmitting draft shocks to said shock absorbing 130 mechanisms.

8. In car construction, the combination with 135 pairs of longitudinally extending sills at opposite sides of the car; of stop means on each pair of sills; shock absorbing means at opposite sides of the car buttressed against said stop means of the sills respectively in both buff and draft; a transversely disposed pressure transmitting member at the end of the car, said pressure transmitting member having outwardly projecting buffering 140

heads at opposite ends thereof; a coupler connection on said member between the ends thereof; rearwardly extending arms on said member at opposite ends thereof engaging the shock absorbing mechanisms for transmitting buffing shocks thereto; and means having lost motion connections with said member for transmitting draft shocks to said shock absorbing mechanisms.

9. In a draft rigging for cars, the combination 10 with a pair of shock absorbing mechanisms at opposite sides of the end of the car; of a transversely disposed pressure transmitting member at said end of the car, said pressure transmitting member having outwardly projecting buffing 15 heads at opposite ends thereof; a coupler connection on said member between the ends thereof; rearwardly extending arms on said member at opposite ends thereof engaging the corresponding shock absorbing mechanism for transmitting buffing shocks thereto; and yoke means enclosing each of said shock absorbing mechanisms, each of said yoke means having a lost motion connection with said member to permit inward movement of said member with respect to the yoke means in buff, said connection transmitting the draft forces from said member to said yoke during outward movement of said member in draft.

10. In a draft rigging for cars, the combination 30 with longitudinally extending sills at opposite sides of the car; of stop means on each sill; shock absorbing means carried by each sill, said shock absorbing means being compressible against said stop means in both buff and draft; a transversely extending beam 35 at the end of the car adapted to receive

buffing forces from an adjacent car; means at the midsection of the beam for connecting the beam to said adjacent car to receive draft forces therefrom; and means for transmitting the draft and buffing forces from said beam to all of said 80 shock absorbing means.

11. In a draft rigging for cars, the combination with longitudinally extending sills at opposite sides of the car; of shock absorbing means supported at opposite sides of the car; fixed 85 stops on said sills forming abutments for said shock absorbing means in buff and draft; a transverse buffing beam at the end of the car movable inwardly in buff and having pressure-transmitting means associated therewith engaging the forward end of said shock absorbing means to transmit buffing forces thereto; means connected to said beam engaging the rear end of said shock absorbing means to transmit draft forces thereto; and a draft connection midway 90 between the ends of the beam for transmitting pulling forces thereto.

12. In a draft rigging for cars, the combination with longitudinal side sills on the car; of a transverse buffing beam at the end of the car extending from one sill to the other; means at the center of said beam for connecting the same to an adjacent car to receive pulling forces therefrom; a pulling element connected to each end of the beam; cushioning means supported on 105 each of said sills yieldingly opposing inward movement of said buffing beam and outward movement of the pulling element; and fixed stop means on said sills against which said cushioning means is compressed.
